UNITED STATES PATENT OFFICE.

AARON P. STORRS, OF OWEGO, NEW YORK.

LAMP-CHIMNEY.

SPECIFICATION forming part of Letters Patent No. 792,473, dated June 13, 1905.

Application filed February 1, 1904. Serial No. 191,449.

To all whom it may concern:

Be it known that I, AARON P. STORRS, a citizen of the United States, residing in Owego, in the county of Tioga and State of New York, have invented a certain new and useful Improvement in Lamp-Chimneys, of which the following is a description.

The present invention relates to improvements in lamp-chimneys for use in connection with incandescent gas-burners, but particularly of that type in which the air is admitted to the outside of the mantle through openings in the chimney, although the invention is not limited to chimneys of that character.

15 The main object of my invention is to produce a chimney, preferably, though not necessarily, of mica, which will have combined with it the burner-cap and a support for the mantle, the whole being arranged to form a

20 new article of manufacture which will be an entirety and can be sold ready with the mantle in place for direct attachment to the burner.

A further object is to provide means for supporting the mantle without the need of the 25 side rod heretofore used.

A further object is to provide means for supporting the mantle within the chimney so securely that it will not be deranged in transportation.

30 In carrying out my invention I provide a chimney of a transparent material with a base-plate upon which a projection is carried, which may constitute a burner-cap and which extends into the chimney and serves as a support for the lower extremity of the mantle.

The upper end of the mantle is carried by a removable cross-bar, so that the mantle may be removed and a fresh one substituted. The chimney, with the projection and mantle, may 35

40 be readily attached to the commercial form of burner by the removal of the cap from the latter, the chimney with the mantle taking its place and being supported thereby without engagement with the gallery.

45 The chimney is preferably made of mica panels perforated near the bottom for the admission of air to the outside of the mantle and supported upon a metal base-plate which has a central opening adapted to surround the 50 burner. This central opening connects with

a cylindrical projection, which serves as a support for the lower end of the mantle, and carries the upper gauze, thereby forming a burner-cap. At the upper part of the mica chimney is arranged a cross-bar of some metal 55 not readily affected by heat. The bar is formed at its center with a loop, from which the mantle is supported. The ends of the cross-bar are preferably flattened and shouldered and engage within rectangular openings 60 formed within a band which forms the upper edge of the chimney, whereby the flattened ends prevent the rod from turning and the shoulders prevent it from being displaced longitudinally. A removable extension, of metal 65 or mica, fitting within the upper part of the chimney may be provided as a finish to the chimney and to increase the draft, and this extension may be provided with inclined slots, which will engage with the cross-bar and 70 upon the extension being partially rotated will cause it to engage with the sides of the rectangular openings and will lock it firmly in place.

In order to better understand the nature of 75 the invention, attention is directed to the accompanying drawings, showing one embodiment of the invention, and in which—

Figure 1 represents a side perspective view of a chimney in place upon a burner of well-known design. Fig. 2 is a perspective view of the upper band and extension, the two being separated. Fig. 3 is a top view of the chimney with the extension removed. Fig. 4 is a sectional view of the lower portion of 85 the chimney; and Fig. 5 is a view of the upper part of the chimney, showing a modified way of supporting the cross-bar.

In all of the several views like parts are designated by the same reference-numerals. 90

As shown in Fig. 1, the chimney consists of a number of panels 1, of mica, constituting the transparent portion, bent to the shape shown and secured in position by uprights 2 and to a base 3 and an upper band 4. The 95 mode of securing the mica panels to the uprights 2 and the character of the uprights are described and illustrated in my Patent No. 700,991, of May 27, 1902.

The base 3 (shown in section in Fig. 4) is 100

preferably a disk-shaped piece of metal having an outer flange 5, with an outwardly-flaring upper edge, as shown, and a central opening 6, with a cylindrical projection 7, preferably made integral with the base. When the projection 7 is to be used as a burner-cap, its upper portion is drawn inward at 8 and serves as a support for the upper gauze 9, which is inserted from below and is secured in position by elastic engagement with the sides of the projection 7. Additional means, however, may be used to retain the gauze in position. The lower gauze is carried by the burner, as is well understood. The projection 7 is the same shape and size as the burner-cap and, together with the gauze, when used, may take the place of the cap. The projection 7, it is to be understood, is so proportioned as to make a close fit with the burner, the size of the projection depending upon the character of the burner used. The lower edges of the mica panels 1 may be protected by a lower band 10, which will rest within the flange 5 of the base; but this band is not absolutely essential, as the panels may be in direct engagement with the flange. The uprights 2 are provided with tongues 11, which are preferably integral and which pass through openings 12 in the base. These tongues being bent up, as shown in Fig. 4, serve as a locking means for securing the base to the rest of the structure.

The lower end of the mantle 13 surrounds the projection 7, and its upper end is supported from the middle of the cross-bar 14, the ends of which are supported by the chimney. This cross-bar takes the place of the usual side rod carried by the burner-cap. The side rod in burners of the type in which the present invention is especially applicable being close to the mantle is subject to great heat and may become distorted or destroyed thereby.

As shown in Fig. 2, the upper band 4 is provided with oppositely-arranged openings 15, within which the extremities of the cross-bar 14 rest. The bar is formed of a round rod or wire with the ends flattened at 16, forming shoulders 16^a, and the openings 15 are preferably of rectangular shape, so that the bar will not turn; but this construction is not necessary. The openings are of less width than the shoulders 16^a, which abut against the inner surfaces of the upper ring 4 and prevent horizontal displacement of the cross-bar.

As shown in Fig. 5, the cross-bar may pass through openings formed directly in the mica panels, each opening being provided, if desired, with an eyelet 17. In the modification the cross-bar is not necessarily flattened; but the shoulders 16^a may be formed by upsetting the wire near each extremity.

The cross-bar 14 is preferably made of nickel or some other heat-resisting material and is formed near its center with a double

loop 18 for the purpose of supporting the mantle. The peculiar mounting of the cross-bar and the provision of the latter with a central loop is to securely hold the mantle in place, irrespective of the position it may assume. The shape of the loop is shown in Fig. 3, there being sufficient space left between the turns of the loop to permit the supporting-loop of the mantle to be slipped within the wire loop.

The extension 19 is preferably made of some light sheet metal, such as aluminum, or of sections of mica and is of the proper size to readily enter the ring 4, a flange 20 serving to support the extension. Two inclined slots 21 on opposite sides of the lower portion of the extension are adapted to engage with the ends of the cross-bar 14 and upon the extension being partially rotated will lock itself to the chimney and at the same time firmly secure the cross-bar in position. Suitable clips 22, carried by the uprights 2, serve to support the shade, as described by my Patent No. 624,568, of May 9, 1899. The lower portion of each of the mica panels is preferably perforated, as at 23, for the admission of air to the chimney; but these holes, if desired, may be placed within the base 3. The parts of the chimney are assembled by first so placing the mantle that the lower end will surround the projection 7 and with its loop in engagement with the loop 18, one end of the cross-bar 14 being introduced within one of the openings 15. By pressing the sides of the ring 4 together, so as to distort it and cause it to assume the shape shown in broken lines in Fig. 3, the other extremity of the cross-bar may be readily inserted within the opening 15, and upon the pressure being removed the ring will assume its normal shape, securing the cross-bar in position. The extension may then be applied by introducing it within the upper band 4. The inclined slots 21 will thus be caused to engage with the cross-bar, and upon the extension being partially turned it will be locked in place and the cross-bar be secured in position.

When thus assembled, the chimneys, with the mantles therein, may be placed within boxes or otherwise packed and shipped, the purchaser merely having to attach the entire device to the burner in place of the burner-tip without having to handle the mantle directly.

It is to be understood that the chimney is supported entirely from the burner 24 by engagement of the projection 7 therewith and without engagement with the gallery.

If a mantle is to be replaced, the used one may be readily removed and a new one inserted.

It is to be understood that the chimney may be made of glass, if desired, and that various portions of the device may be omitted without departing from the invention.

Having now described my invention, what I claim, and desire to secure by Letters Patent, is—

1. A new article of manufacture comprising in combination a chimney which comprises a transparent portion and a base, the base having a central opening, and a projection, and a mantle, the lower end of the mantle surrounding the projection and means for supporting the mantle.
2. A new article of manufacture comprising in combination a chimney which comprises a transparent portion and a base, the base having a central opening and a projection, a mantle, the lower end of the mantle surrounding the projection, and means for supporting the upper end of the mantle irrespective of the position the chimney may assume.
3. A new article of manufacture comprising in combination a chimney which comprises a transparent portion and a base, the base having a central opening and a projection, a mantle, the lower end of the mantle surrounding the projection, means for supporting the upper end of the mantle irrespective of the position the chimney may assume, such means comprising a cross-bar engaging with the chimney, and having a double loop intermediate its ends for engaging the mantle.
4. A new article of manufacture comprising in combination a chimney, which comprises a transparent portion and a base, the base having a central opening, and a cylindrical projection, a gauze in said projection forming a burner-cap, and a mantle, the lower end of the mantle surrounding the projection and means for supporting the mantle.
5. A new article of manufacture comprising in combination a chimney, which comprises a transparent portion and a base, the base having a central opening, and a cylindrical projection, a gauze in said projection forming a burner-cap, and a mantle, the lower end of the mantle surrounding the projection, means for supporting the upper end of the mantle, irrespective of the position the chimney may assume.
6. A new article of manufacture comprising

in combination a chimney, which comprises a transparent portion and a base, the base having a central opening, and a cylindrical projection, a gauze in said projection forming a burner-cap, and a mantle, the lower end of the mantle surrounding the projection, means for supporting the upper end of the mantle irrespective of the position the chimney may assume, such means comprising a cross-bar engaging with the chimney, and having a double loop intermediate its ends for engaging the mantle.

7. A new article of manufacture comprising in combination a chimney, which comprises a transparent portion and a base, the base having a central opening, and a cylindrical projection, a mantle, the lower end of the mantle surrounding the projection, its upper end supported by a rod engaging in perforations on opposite sides of the chimney.

8. A new article of manufacture, comprising in combination a chimney, which comprises a transparent portion and a base permanently secured to one end thereof, a burner-cap permanently attached to the base, a reinforcing-band secured to the other end of the chimney, a mantle closely engaging the burner-cap with its open end, and with its closed end supported by a rod engaging in perforations in the reinforcing-band, substantially as described.

9. A new article of manufacture comprising in combination a chimney which comprises a transparent portion and a base, permanently secured to one end thereof, a burner-cap permanently attached to the base, a reinforcing-band secured to the other end of the chimney, a mantle closely engaging the burner-cap with its open end, and with its closed end supported by a rod engaging in perforations in the reinforcing-band, shoulders on the rod to prevent movement thereof, and a removable extension carried by and locked to the chimney.

This specification signed and witnessed this 19th day of January, 1904.
